UNITED STATES PATENT OFFICE.

MARJORIE PHYLLIS DYRENFORTH FORTUNE, OF LOS ANGELES, CALIFORNIA.

DESIGN FOR A PENCIL.

57,520.

Specification for Design.

Patented Apr. 12, 1921.

Application filed August 17, 1920. Serial No. 404,272. Term of patent 3½ years.

To all whom it may concern:

Be it known that I, MARJORIE PHYLLIS DYRENFORTH FORTUNE, a citizen of the United States, residing a Los Angeles, in the county of Los Angeles and State of California, have invented a new, original, and ornamental Design for Pencils, of which the following is a specification, reference being had to the accompanying drawing, forming a part thereof.

Fig. 2 is a side elevation thereof.

I claim:
The ornamental design for a pencil as shown.

MARJORIE PHYLLIS DYRENFORTH FORTUNE.
